US0D1094724S

(12) **United States Design Patent** (10) **Patent No.:** **US D1,094,724 S**
(45) **Date of Patent:** **** Sep. 23, 2025**

(54) **SET OF INSTRUMENT CART ARMS**

(71) Applicant: **Auris Health, Inc.**, Santa Clara, CA (US)

(72) Inventors: **Jonathan Mendoza**, San Francisco, CA (US); **Frankie Vazquez**, San Francisco, CA (US); **Toby A. Stopper**, San Francisco, CA (US); **Wonbin Choi**, San Francisco, CA (US)

(73) Assignee: **Auris Health, Inc.**, Santa Clara, CA (US)

(**) Term: **15 Years**

(21) Appl. No.: **29/988,011**

(22) Filed: **Jan. 29, 2025**

Primary Examiner — Rhea Shields

(74) *Attorney, Agent, or Firm* — Paradice & Li LLP

(57) **CLAIM**

The ornamental design for a set of instrument cart arms, as shown and described.

DESCRIPTION

FIG. 1 is a top, front, left perspective view of set of instrument cart arms;

FIG. 2 is a front view of the instrument cart arms;

FIG. 3 is a rear view of the instrument cart arms;

FIG. 4 is a right-side view of instrument cart arms;

FIG. 5 is a left-side view of the instrument cart arms;

FIG. 6 is a top view of the instrument cart arms; and,

FIG. 7 is a bottom view of the instrument cart arms.

In the drawings, the broken lines are for the purpose of illustrating portions of the instrument cart arms, that form no part of the claimed design.

1 Claim, 7 Drawing Sheets
